(57) **CLAIM**

We claim the ornamental design for a portable terminal, as shown and described.

DESCRIPTION

FIG. 1 is a front perspective view of a portable terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines shown in the figures that are immediately adjacent to the shaded areas and define unshaded regions represent the bounds of the claim. All other broken lines including the features within broken line boundaries and the broken lines beneath the front glass at either side of the speaker and the display rectangles are directed to environment. The broken lines form no part of the claimed design.
